(57) **CLAIM**

The ornamental design for a loudspeaker enclosure, as shown and described.

DESCRIPTION

FIG. 1 is a front perspective view of loudspeaker enclosure, showing our new design.

FIG. 2 is a top view of the loudspeaker enclosure of FIG. 1.

FIG. 3 is a bottom view of the loudspeaker enclosure of FIG. 1.

FIG. 4 is a front view of the loudspeaker enclosure of FIG. 1.

FIG. 5 is a rear view of the loudspeaker enclosure of FIG. 1.

FIG. 6 is a left side view of the loudspeaker enclosure of FIG. 1; and,

FIG. 7 is a right side view of the loudspeaker enclosure of FIG. 1.

The broken lines shown in the drawings represent unclaimed portions of the loudspeaker enclosure and form no part of the claimed design.

The interior structural features seen inside the separation of the respective body portions of the loudspeaker enclosure are shown in broken lines and do not form part of the scope of protection.

1 Claim, 7 Drawing Sheets

Related U.S. Application Data

and having an international filing date of Nov. 10, 2017, now Pat. No. Des. 879,071.
